METHOD OF MASKING COLOR TRANSPARENCIES

Henry C. Staehle, Rochester, N. Y., assignor to Eastman Kodak Company, Rochester, N. Y., a corporation of New Jersey

Application March 20, 1941, Serial No. 384,389

7 Claims. (Cl. 154—40)

This invention relates to a method of applying an unexposed sensitive layer to a support and is particularly useful in color correction in masking color reproductions and particularly to a method of masking color transparencies.

The art of masking has been well established particularly by the use of separate plates and films which are processed separately from the color transparency and, after processing, are replaced in register with the color transparency. The chief objection to this procedure is that it is difficult to register the image produced in the masking plate or film with the image in the color transparency, so that the definition of the resulting print is impaired.

Methods have been devised for making the mask integral with the film with which it is to be used. For example, in Evans U. S. Patent 2,203,653, granted June 4, 1940, a masking method is described in which a gold negative mask is formed in the layers of a multi-layer film during color processing of the film. This procedure is not suitable with color transparencies which have been prepared by the amateur or which must be returned to a customer so that they may be used for viewing. Another masking process is described in Ehrenfried U. S. Patent 2,203,652, granted June 4, 1940, which involves the use of a print-out emulsion which is temporarily bound or cemented to a color transparency. The print-out layer is exposed through the color transparency and since a print-out emulsion need not be developed a masking image is formed directly. While this process is useful in many cases, it has the disadvantage that print-out emulsions are difficult to handle in practice and if the element is kept for any length of time after exposure of the print-out emulsions, there is the danger that the print-out layer will be fogged and the masking layer thereby rendered useless.

It is, therefore, an object of the present invention to provide a method for masking a color transparency which does not involve the prior art difficulties. A further object is to provide a method for laminating or bridging a sensitive emulsion layer in contact with a color transparency so that it may be exposed and processed while in contact with the color transparency. Other objects will appear from the following description of my invention.

These objects are accomplished by transferring an unexposed unprocessed photographic emulsion carried on a thin support, to the color transparency, exposing it to light of suitable spectral distribution through the color transparency and developing, fixing, washing and drying it all while attached to the color transparency.

In the accompanying drawing,

Fig. 1 is a sectional view showing the method of transferring the sensitive stripping emulsion to one of a pair of rolls, and

Fig. 2 is a sectional view showing the method of applying the sensitive stripping emulsion to a color transparency.

15 The masking film used according to my invention may be either a thin base film coated with emulsion and subbed or unsubbed on the base side or a dry stripping material. Suitable dry stripping material which may be used according to the preferred embodiment of my invention is described in Nadeau and Starck U. S. Patent 2,266,435, granted December 16, 1941. This film has the following characteristics: A thin layer of film support is coated on a film 20 support of standard thickness under such conditions that the bond between the two supports is easily separated when dried. A suitable masking emulsion is coated on the thin support which constitutes the permanent support for the masking layer. A panchromatic or red-sensitive emulsion is preferably used for the masking layer.

To effect the transfer from the original support to the color transparency, the stripping layer or portion consisting of permanent support and emulsion is separated from the temporary support and as this is being done it is wound upon one of a pair of smooth even rolls adjusted to rather light pressure. Soft rubber rolls are suitable for this purpose. When the entire stripping 25 portion has been removed from its original support and has been wound onto the roll, the color transparency is passed between the rolls in the opposite direction and at the same time the color transparency or the base side of the stripping emulsion is separated from the temporary support and wound onto the other roll.

30 35 40 45 50 The base side of the stripping film is moistened with a suitable cement. As soon as the base of the stripping film comes in contact with the color transparency, a firm bond is effected which will not loosen during subsequent processing operations and will not allow any of the proc-

essing solutions to come in contact with the image of the color transparency. If a suitable cement is used, the nature of the bond is such that the masking film may be stripped off when no longer needed and the color transparency returned to its original state. Other cements may be used if a permanent bond is desired.

A suitable cement for laminating the base side of the stripping film to the emulsion of the color transparency has the following composition:

Gelatin	grams	0.5
Acetic acid	do	3
Water to	cc	100

Another suitable cement is one consisting of a dispersion of acrylic ester resin in water containing a wetting agent.

The masking emulsion may also be applied to the base side of the color transparency in which case a diffuse type mask is obtained. In some cases this diffuse mask applied to the base has a distinct advantage over the mask applied to the image side of the color transparency. In case the color transparency has a gelatin backing, the same cement may be used as is used for cementing the mask film to the image side of the color transparency.

The purpose and function of the masking layer as applied to color transparencies are well known. The purpose of the mask is first, to reduce the overall contrast of the color transparency and second, to increase the color saturation.

The contrast of the color transparency is reduced in that the mask is a low contrast negative of the original. It may be a positive mask applied to a color transparency negative or it may be a negative mask applied to a color transparency positive. In any case it produces a desirable lowering of the contrast of the color transparency.

Color saturation is usually increased by using a panchromatic or red-sensitive emulsion which is exposed through the colored original to red light. The exposure is, therefore, controlled almost entirely by the blue-green dye of the color transparency, assuming that the subtractive color process is used. The result is that a silver image is formed in the masking layer only over those layers which transmit red light freely and very little density is produced in the masking layer behind the blue, cyan, or green areas.

My invention will now be described with particular reference to the accompanying drawing which illustrates the preferred embodiment of the invention. As shown in Fig. 1, a stripping film comprising a temporary support 10 of paper or cellulose ester having thereon a permanent support 11 of suitable cellulose ester and panchromatic emulsion layer 12 is passed downwardly through soft rubber rolls 13 and 14 and the portion of the film comprising the permanent support 11 and emulsion layer 12 is wound onto the roll 14 with the emulsion side in contact with the roll. The temporary support 10 being relatively thick does not tend to wrap around the rolls but passes between them leaving the sensitive portion of the stripping film on the roll 14. This is readily accomplished by the use of a suitable dry stripping film such as that referred to above.

When the sensitive portion of the stripping film is entirely wound onto the roll 14, the color transparency is passed in the opposite direction through the rolls as illustrated in Fig. 2 of the

drawing. The color transparency may consist of a support 15 having thereon layers 16, 17 and 18 containing colored images representing each of the three primary colors. It is obvious that a single layer film or other type color transparency may also be used for receiving the masking layer.

Before the color transparency comes into contact with the masking film, the latter is coated with a suitable adhesive material, for example, by means of applicator rolls 19 and 20 which receive the adhesive from a reservoir 21. The adhesive may also be applied by other suitable means to the support 11 of the masking layer before it touches the color transparency. The pressure of the rolls 13 and 14 produces a firm even bond between the color transparency and the support 11 of the masking film.

The mask described above may be used on any type color transparency such as motion picture film, cut sheet film or glass plates. More than one mask may, of course, be applied to a color transparency either on one side or on both sides of the transparency. It is obvious that, in its broader aspects, this invention is capable of numerous applications whenever it is desirable or convenient to manufacture a photographic layer separately from the support to which it is to be permanently applied, and particularly where the permanent support is of glass or other rigid or frangible material not readily and cheaply transported. The examples and method described herein are illustrative only and it is to be understood that my invention is to be considered as limited only by the scope of the appended claims.

I claim:

1. The method of laminating a light-sensitive masking layer to a color transparency, which comprises wrapping a thin-base, light-sensitive photographic element on a cylindrical surface of one of a pair of rolls, passing the color transparency between the rolls in contact with the light-sensitive element, and cementing the light-sensitive element to the color transparency.

2. The method of laminating a light-sensitive layer to a rigid support, which comprises wrapping a thin-base, light-sensitive photographic element in one direction onto a resilient cylindrical surface to form a smooth coil of the element on the cylindrical surface and then transferring the photographic element in the opposite direction from the cylindrical surface onto a rigid plane surface on which it is to be exposed, and cementing the photographic element to the plane surface while pressing it into close contact with said plane surface by means of said resilient cylindrical surface.

3. The method of sensitizing a rigid sheet that comprises supplying a roll of flexible dry stripping material including a support and a portion including an unexposed photographic emulsion layer strippable therefrom while dry, stripping said portion from the support and applying it to the sheet before exposure of said emulsion, at the same time supplying an adhesive between the sheet and portion and pressing them into close contact, whereby the unexposed photographic layer is securely attached to the sheet.

4. The method of sensitizing a rigid sheet that comprises supplying a roll of flexible dry stripping material including a support and a portion including an unexposed photographic emulsion layer, said portion being strippable from the support while dry, stripping said portion from the

support and applying it to a rigid sheet, at the same time supplying an adhesive between the sheet and portion and pressing them into close contact, the support being stripped in a dry state from said portion prior to exposure of the resulting sensitized sheet.

5. The method of laminating a light-sensitive masking layer to a color transparency, which comprises transferring the light-sensitive element of a stripping film having a temporary support from said temporary support to a cylindrical surface of one of a pair of rolls, passing the color transparency between the rolls in contact with the light-sensitive element, and cementing the light-sensitive element to the color transparency with that surface of the light-sensitive element outermost which was originally outermost.

6. The method of laminating a light-sensitive masking layer to a color transparency, having an emulsion on one side thereof, which comprises transferring the light-sensitive emulsion layer and permanent support of a stripping film

including a permanent support, temporary support and sensitive emulsion layer, from said temporary support to a cylindrical surface of one of a pair of rolls, passing the color transparency between the rolls with the emulsion side of said transparency in contact with said permanent support, and cementing the permanent support to the color transparency.

7. The method of laminating a light-sensitive masking layer to a color transparency, having an emulsion on one side thereof, which comprises transferring the light-sensitive emulsion layer and permanent support of a stripping film including a permanent support, temporary support and sensitive emulsion layer from said temporary support to a cylindrical surface of one of a pair of rolls, passing the color transparency between the rolls with the emulsion side of said transparency in contact with said permanent support and cementing the permanent support to the color transparency with a dilute solution of gelatin and acetic acid.

HENRY C. STAEHLE.
